DESIGN FOR A DRESS

Julius Baron, Brookline, Mass., assignor to Baron
Dress Company, Boston, Mass.

Application December 11, 1933, Serial No. 50,028

Term of patent 3½ years

To all whom it may concern:

Be it known that I, JULIUS BARON, a citizen of the United States of America, residing at Brookline, Massachusetts, have invented a new, original, and ornamental Design for a Dress, of which the following is a specification, reference being had to the accompanying drawing, forming a part thereof.

Fig. 1 is a perspective, front view of a dress embodying my design; and

Fig. 2 is a perspective, rear view thereof.

I claim:

The ornamental design for a dress substantially as shown.

In testimony whereof I have signed this specification.

JULIUS BARON.
